UNITED STATES PATENT OFFICE.

STANLEY SOKOLOWSKI AND JAKOB FORGIEL, OF TAUNTON, MASSACHUSETTS.

NON-SINKABLE SHIP.

1,391,421.

Specification of Letters Patent. Patented Sept. 20, 1921.

Application filed April 8, 1921. Serial No. 459,676.

To all whom it may concern:

Be it known that we, STANLEY SOKOLOWSKI and JAKOB FORGIEL, citizens of the United States and Poland, respectively, re-

5 siding at Taunton, in the county of Bristol and State of Massachusetts, have invented certain new and useful Improvements in Non-Sinkable Ships, of which the following is a specification.

10 This invention relates to a non-sinkable ship, and it has for an object to provide a novel arrangement of buoyant devices for sustaining the ship in the event of damage to the hull thereof.

15 A further object is to provide means of this kind which is arranged within the confines of the hull when not in use and extended laterally when in use.

For further comprehension of the invention, and of the objects and advantages thereof, reference will be had to the following description and accompanying drawings, and to the appended claims in which the various novel features of the invention are 25 more particularly set forth.

Figure 1 of the drawings is a side view of a ship having the invention applied thereto.

Fig. 2 is a plan view thereof.

30 Fig. 3 is an enlarged partial plan view of the ship.

Fig. 4 is a transverse section on the line 4—4 of Fig. 3.

35 Fig. 5 is a detail view showing the means for connecting the main drums to the power drive.

The hull of the ship is indicated at 10 and may be, generally speaking, of the usual construction, the main deck of the ship being shown at 11. Formed in opposite sides 40 of the hull 10, and extending the major portion of the length thereof, are recesses or pockets 12 which open outwardly, their inner walls being formed by plates 13, while they are normally closed by doors 14 hinged 45 to the hull at their upper edges as at 15, and extending flush with the sides of the hull.

Carried in the pockets 12 are extensible air bags 17 which may be suitably attached to the doors 14 and the pocket walls 13, having 50 suitably formed plaits 17' on their ends and bottom for folding and extension purposes.

The doors 14 are held in closed position by means of ropes 18 attached to the inner faces thereof and wound on drums 19 fixed 55 on vertical shafts 20 extending downwardly through the pockets 12 and supported by

suitable bearings, suitable air tight packing glands engaging these shafts where they pass through the top and bottom pocket walls.

60 Fixed on these shafts 20, just above the deck 11, are ratchet wheels 21, the upper ends of the shafts extending a distance above the deck and having hand wheels 22 fixed thereon. Fixed on pins 23 passing through the deck 11 are pawls 24 adapted to engage the ratchet wheels 21. Fixed on the pins 23, under the deck 11, are arms 25, these arms being connected by a rod 26 extending transversely of the ship under the deck 11 where 65 by both pawls are operated in unison. Tension springs 28 connected to the rod normally hold the pawls engaging the wheels 21.

70 For swinging the doors 14 open I attach thereto a pair of ropes 30 which extend upwardly outside the hull 10, and inwardly over the pulleys 31 on the ship's gunwales, the inner ends of these ropes being normally unattached to the door opening mechanism.

75 The door opening mechanism comprises a pair of drums 34 journaled on suitable standards 35, these standards being mounted on hinged hatch-way doors 36 in the deck 11. The drums may be individually rotated by means of crank handles 37 fixed on auxiliary shafts on each which is a gear pinion 39 meshing with a gear 40 on the drum shaft 41. To the drums are fixed a pair of oppositely winding ropes 34' which are adapted to be 80 attached by any suitable hook and eye means such as 34' to the upper ends of the ropes.

85 The drums 34 may also be rotated in unison by a motor 45 connected by gearing 46 to a shaft 47 alined with the drum shafts 41 and having slidably sleeves such as 48 on opposite ends adapted to effect a driving connection therebetween and the drum shafts.

90 Under normal conditions the doors 36 remain in the open position shown in dotted lines in Fig. 4 to give access to the hatchway, the doors being swung to the full line position when the invention is to be put into use. Upon the underside of each of the doors 36, adjacent the free edge thereof, is a cam projection 50 which is adapted to engage a lug 51 on the rod 26 when the door is closed and move said rod in a direction to free the pawls 24 from the ratchet wheels 21.

100 It is believed that the manner of use of our invention will be readily understood 105 from the above description. Under normal condition the ropes 18 hold the pocket doors

14 closed, the pawls 24 preventing unwinding movement of these ropes from the drums 19. When the device is to be brought into use the doors 36 are closed, the cams 50 engaging lugs 51 and freeing the pawls 24 from the ratchet wheels 21. The ropes 30 and 34' are connected together, the sleeves 48 engaged with the drum shafts 41, and the drums rotated to swing the doors 14 upwardly, expanding the bags 17 which have one-way air valves 60 leading thereinto through the doors 14.

Having thus described our invention what we claim as new and desire to protect by Letters Patent of the United States is as follows:

1. A ship having a pocket in each side of the hull thereof, hinged doors flush with the hull closing said pockets, air tight bags in said pockets, ropes attached to the inner sides of said doors to hold the same closed, ropes attached to the outer sides of said doors to open the same, and means mounted on the deck of the ship for releasing said first ropes and pulling on said second ropes.

2. A ship having a pocket in each side of the hull thereof, hinged doors flush with the hull closing said pockets, means holding said door closed, a hatch-way door adapted when swung to closed position to release said means, and winding mechanism on said hatch-way door for opening said pocket doors.

3. A ship having a pocket in each side of the hull thereof, air tight bags in said pockets, hinged doors flush with the hull closing said pockets, means including a pair of pawls holding said doors closed, a rod connecting said pawls to operate in unison, a spring

normally holding said rod with the pawls in operative position; a hinged hatch-way door, a cam projecting on said door adapted to move said rod to swing the pawls to inoperative position when the hatch-way door is closed, and winding mechanism on said hatch-way door for opening said pocket doors.

4. A ship having a pocket in each side of the hull thereof, air tight bags in said pockets, hinged doors flush with the hull closing said pockets, means including a pair of pawls holding said doors closed, a rod connecting said pawls to operate in unison, a spring normally holding said rod with the pawls in operative position; a hinged hatch-way door, a cam projecting on said door adapted to move said rod to swing the pawls to inoperative position when the hatch-way door is closed and winding mechanism on said hatch-way door for opening said pocket doors.

5. A ship having a pocket in each side of the hull thereof, hinged doors flush with the hull closing said pockets, air-tight bags in said pockets, ropes attached to the inner sides of said doors to hold the same closed, shafts extending through said pockets, drums on said shaft to which said ropes are attached, and ratchet and pawl means holding said shafts against rotation.

In testimony whereof we have affixed our signatures.

STANLEY SOKOLOWSKI
JAKOB FORGIEL.
